UNITED STATES PATENT OFFICE

FRANK PEKAR, OF BRIDGEPORT, CONNECTICUT

BURGLARPROOF SAFETY WINDOW LOCK AND ANTIRATTLING DEVICE

Application filed June 4, 1929. Serial No. 368,365.

This invention relates to latches and has special reference to a sash latch which I preferably term an improved burglar safety window lock and anti-rattling device.

One important object of the invention is to improve the general construction of devices of this character.

A second important object of the invention is to improve the window latch shown and described in my prior Patent 1,661,634 of March 6, 1928.

A third important object of the invention is to provide a form of window latch wherein the spring which normally urges the latch into latching position also acts to hold the latch in free position.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a section through a pair of window sash showing one form of the improved latch in side elevation.

Figure 2 is a view of this form of latch also in side elevation and showing the latch in free position.

Figure 3 is an end view of the latch from the left hand of Figure 2.

Figure 4 is a detail top view of the pawl member of the latch.

Figure 5 is a section on the line 5—5 of Figure 3.

Figure 6 is a side view of a somewhat modified form of latch.

Figure 7 is an end view thereof.

Figure 8 is a section on the line 8—8 of Figure 7.

Figure 9 is a plan view of the modified form.

In both forms of the invention there is provided an attaching device or housing in the form of a box 10 open at the top and front and provided at its sides with attaching feet 11 by means of which it may be secured to

the top of a roller sash 12 adjacent one side thereof so that the pawl, which will be presently described, may engage the side frame member 13 of the upper sash 14. Through the side walls in each form extends a pivot pin 15 and on this pivot pin is pivoted a pawl which comprises a U-shaped member 16 preferably formed of stamped metal and carrying between its sides a rubber friction member 17 which normally engages the side member 13 when the latch is in use.

In the form of the invention shown in Figure 6 prongs 18 extend forwardly to bite into the window material if the upper sash is forced down or the lower sash forced up, thus aiding the frictional effect of the member 17. These two forms are substantially alike except in relation to their spring element and in the form shown in Figures 1 to 5 a coil spring 19 is wound on the pin 15 between the sides of the pawl 16. One end of the wire as 20, forming this spring, extends through an opening 21 in the rear wall of the housing 10 while the other end of said wire extends through a transverse opening 22 formed in the top rear end of the pawl 16, this last end of the spring being flattened as at 23 to form a thumb piece. Leading downwardly diagonally from the top edge of the rear wall of the housing 10 is a slot 24 which terminates in a notch 25 and by reason of the slot 22, and the slot 24 and its notch the pawl may be tilted into the position shown in Figure 2 by simply pressing on the flattened end 23 of the spring and guiding it through the slot 24 into the notch 25 where it will hold the pawl raised. Of course, when released this spring acts to force the pawl into the position shown in Figure 1.

In Figures 6 to 9 the pin 15 is surrounded by a coil spring 26 having an end 27 engaging the front 28 of the pawl 16. The other end of this spring is supported in a diagonal notch 29 formed in the rear wall of the housing 10. In the top rear portion of the pawl 16 in this form is a slot 30 terminating in a notch 31. Now, so long as the end 32 of the spring is not engaged in the notch 31 this spring will act to force the pawl into active position but, if the end 32 of the spring be

slid to the right so that it can pass through the slot 30 into the notch 31 then the pawl 16 will be held raised as shown in Figure 8, being readily released by moving the spring end 32 laterally.

5 There has thus been provided a simple and efficient device of the kind described and for the purpose specified.

It is obvious that minor changes may be
10 made in the form and construction of the invention without departing from the material spirit thereof. It is not, therefore, desired to confine the invention to the exact form herein shown and described, but it is desired
15 to include all such as properly come within the scope claimed.

Having thus described the invention, what is claimed as new, is:

1. In a sash latch, a housing open at the
20 front and top and having means for attachment to a window sash, a pawl pivoted in said housing and projecting forwardly to engage a selectively fixed object adjacent said sash, a spring urging said pawl into object
25 engaging active position and having one end projecting for manipulation to shift the spring to position to hold the pawl away from the object, said pawl having means at its rear end to hold the said spring end, and means
30 at the rear of the housing to engage and hold said spring end with the pawl in raised position.

2. In a sash latch, a housing open at the front and top and having means for attachment to a window sash, a pawl pivoted in said housing and projecting forwardly to engage a selectively fixed object adjacent said sash, a spring urging said pawl into object
35 engaging active position and having one end projecting for manipulation to shift the spring to position to hold the pawl away from the object, said pawl having means at its rear end to hold the said spring end, and said housing being slotted at its rear wall to provide
40 a laterally extending portion beneath which said spring end is engageable.

3. In a sash latch, a housing open at the front and top and having means for attachment to a window sash, a pawl pivoted in
50 said housing and projecting forwardly to engage a selectively fixed object adjacent said sash, a spring urging said pawl into object engaging active position and having one end projecting for manipulation to shift the
55 spring to position to hold the pawl away from the object, said pawl having a diagonal slot in its rear top portion through which said spring end extends, and said housing having a diagonal slot extending downwardly from
60 its top edge and terminating in a downwardly facing notch at its inner end.

In testimony whereof I affix my signature.

FRANK PEKAR.
